US00D747344S

(12) **United States Design Patent**
Balles et al.

(10) **Patent No.:** **US D747,344 S**
(45) **Date of Patent:** **** Jan. 12, 2016**

(54) **DISPLAY SCREEN WITH GRAPHICAL USER INTERFACE**

(71) Applicant: **Apple Inc.**, Cupertino, CA (US)

(72) Inventors: **Scott Balles**, Brooklyn, NY (US); **Gary Butcher**, San Jose, CA (US); **Imran Chaudhri**, San Francisco, CA (US); **Jonathan P. Ive**, San Francisco, CA (US); **Tiffany Jon**, Sunnyvale, CA (US); **Ernest Rowe**, Cupertino, CA (US); **Alessandro Francesco Sabatelli**, Cupertino, CA (US); **Eric Lance Wilson**, San Jose, CA (US)

(73) Assignee: **Apple Inc.**, Cupertino, CA (US)

(**) Term: **14 Years**

(21) Appl. No.: **29/462,426**

(22) Filed: **Aug. 2, 2013**

(51) LOC (10) Cl. **14-03**

(52) U.S. Cl.

USPC **D14/489**

(58) **Field of Classification Search**

(57) **CLAIM**

The ornamental design for a display screen with graphical user interface, as shown and described.

DESCRIPTION

FIG. 1 is a front view of a display screen or portion thereof with graphical user interface showing our new design; and, FIG. 2 is another embodiment thereof.

The outermost dashed broken lines in the figures show a display screen or portion thereof, and form no part of the claimed design. The other dashed broken lines in the figures show portions of the graphical user interface that form no part of the claimed design.

The dot-dash broken lines in the figures and the areas within the dot-dash broken lines show portions of the graphical user interface that form no part of the claimed design.

1 Claim, 2 Drawing Sheets
